WINCH CONTROL

Edward M. Claytor, Wilkinsburg, Pa., assignor to
Westinghouse Electric & Manufacturing Company,
East Pittsburgh, Pa., a corporation of
Pennsylvania

Application May 26, 1934, Serial No. 727,747

9 Claims. (Cl. 254—172)

My invention relates to control systems for motors and more particularly to systems of control for motors operating winches or similar equipment.

5 One object of my invention is to limit the tension of the cable in a winch or hoist to prevent breakage thereof or injury to the operating equipment.

Another object of my invention is the provision 10 of a system of control for a winch, or other hoisting equipment adapted for mooring, towing, hoisting or other purposes which shall automatically take up slack on a moving or connecting line, and which shall automatically pay out such line 15 when the tension therein has reached a predetermined value.

A further object of my invention is to measure 20 the weight or the tension in a winch cable when the motor operating the winch is stopped by an overload and to restart the motor only when the tension or weight thus measured has decreased to a selected value.

Other objects and advantages of my invention 25 will become more apparent from a study of the following specification and of the accompanying drawing in which the single figure is a diagrammatic showing of one embodiment of my invention comprising a winch, a driving motor therefore, a brake structure, and the electrical control 30 for the motor.

Referring more particularly to the drawing, a winch 1 is connected to a driving motor 2 by suitable gearing 67. An electromagnetic brake 3 is associated with the motor shaft, which brake 35 holds the winch drum stationary when the motor 2 is deenergized, at which time the electromagnetic 40 of the brake is also deenergized. A manually-operable controller 4 is provided to control the direction of operation and the speed of the motor 45 2 by means of electromagnetic contactors 5.

Generally stated, the illustrated system of control limits the tension in the cable 72 by an appropriate energization and deenergization of the motor 2 and, if need be, reverse energization 50 thereof. If the motor be operating to hoist a load, the control arm 7 having been moved in the hoist direction, and the load on the motor exceeds a predetermined amount for the speed setting of the motor as determined by the setting 55 of controller 4, an overload relay 34 will operate to deenergize the motor 2. The magnetizing coil of the brake mechanism 3 will also be thus de-energized whereupon the brake mechanism, having a resiliently mounted casing or spring-biased base 55 and a spring-pressed brake shoe 57

mounted therein, oscillates to some extent about the axis of the brake drum, thereby moving the arm 74 and thus the link 63 upwardly to move the gear 65 in a clockwise direction through the crank arm 64. Shaft 66 is thus rotated in a counter-clockwise direction to actuate contact arm 11 in a counter-clockwise direction a corresponding amount.

5 The arm 74 is provided with a shock-absorbing device 100. This device has a piston 101 in a cylinder 102 provided with a by-pass tube 103 for establishing a complete or closed circuit between the ends of the cylinder. A throttle valve 104 is disposed in the tube whereby the shock absorbing effect may be varied at will. A suitable 10 liquid is disposed in the tube and when the arm 74 is operated the piston moves the liquid in the cylinder through the valve 104. The shock-absorbing device, as described, prevents violent actuation of arm 74 and thus provides for a 15 smoother and more accurate control.

20 If the tension is very greatly increased in the cable 72 from any cause whatsoever arm 11 is moved farther in a counter-clockwise direction by an amount sufficient to reverse the connections 25 for the motor, as hereinafter more fully set forth, in which case the motor operates in the reverse direction for a short interval of time to pay out the cable 72, thereby relieving the tension in the cable.

30 A better understanding of my invention can possibly be had from the study of a typical operating cycle. Assuming that the attendant wishes to hoist a load at the maximum speed, he will thereupon move the plate 6 of the controller 35 4 by means of the control arm or handle 7 in a counter-clockwise direction whereby contact arm 11 will successively engage plate 6 in positions a, b, and c, respectively. In position a a circuit is established from the energized conductor 13 40 through the conductor 14, arm 11 of the controller 4, controller segment 10, the brush 15, conductor 16, actuating coil 17 of the directional contactor 18, conductor 19, and contact members 73 of normally closed overload relay 34 to the energized conductor 20. Operation of the directional contactor 18 closes the contact members 23, 27 and 37, thereby establishing circuits for the motor 2 and for the magnetizing coil 36 of the 45 brake 3, respectively.

50 The motor circuit may be traced from the energized conductor 13 through conductor 21, field winding 22 of the motor 2, contact member 23, conductor 24, armature 25, conductor 26, contact members 27, conductors 28 and 29, resistor sec- 55

tions 30 and 31 of the accelerating resistor 32 and the main coil 33 of the overload relay 34 to the energized conductor 20. The circuit for the magnetizing coil 36 of the brake 3 may be traced 5 from the energized conductor 21 through coil 36, and contact members 37 of closed directional contactor 18 to the energized conductor 19. Energization of the coil 36 moves the brake shoe 57 toward the left, thereby releasing the shaft of 10 the motor 2, whereupon the motor will operate at its slowest speed, since both of the accelerating resistor sections 30 and 31 are in circuit with the motor, to hoist the load.

It should be understood that arm 11 being 15 mechanically coupled to the arm 74 of the oscillating case 55 of the brake will take a position depending upon the tension in the cable 72 when the brake shoes 57 are set as shown, namely when magnetizing coil 36 is deenergized and the spring 20 56 moves the brake shoe 57 toward the right. However, arm 11, by an appropriate adjustment of the relative tensions of the biasing springs 58 and 59 on arm 74 of brake case 55, by means of the adjusting nut means 60 and 61, occupies the 25 illustrated neutral or off position for a normal or desirable tension in the cable 72 during normal operation.

Movement of the handle 7 by a greater amount in the counter-clockwise direction, namely to the 30 position *b*, will establish a circuit for the first accelerating contactor 41 from the energized conductor 14, through arm 11, controller segment 9, brush 38, conductor 39, and actuating coil 40 of the accelerating contactor 41 to the energized 35 conductor 19.

The movement of the handle 7 to the full speed position *c*, establishes a circuit from the energized conductor 14 through arm 11, controller segment 8, brush 43, conductor 44, and actuating 40 coil 45 of the accelerating contactor 46 to the energized conductor 19. The described operation of the accelerating contactors 41 and 46 effects the shunting of the accelerating resistor sections 31 and 30, respectively, to thus apply full voltage 45 to the motor 2.

In my invention, I provide a special overload relay 34 which is automatically calibrated to operate to relieve the tension in the cable 72 when an overload having a definite relation to the speed 50 setting of the motor occurs. Coil 33 of the overload relay 34 carries the armature current of the motor whereas coil 71, additive in effect to the coil 33, is connected to the energized conductors 13 and 20 by a circuit which may be traced from energized conductor 13 through conductor 14, flexible conductor 75, adapted to be connected to a contact member on the movable contact plate 6, either resistor section 68 or section 69, depending 55 on the direction of movement of the arm 7, and conductor 70 to the actuating coil 71 of the overload relay 34 to conductor 76 which conductor will of course, be connected to the energized conductor 19 when either one of the contactors 18 or 60 51 have operated. It should be noted that the coil 71 is connected on the left hand side of the main contact members 73 of the overload relay 34 so that coil 71 is deenergized when the contact members 73 open. It should be noted that movement of the handle 7 in a counter-clockwise 65 direction inserts more and more sections of the resistor 68 in circuit with the coil 71, thereby decreasing the effect of coil 71 for higher and higher speeds. The overload relay 34 is thus automatically calibrated so as to require larger currents in coil 33 with higher speeds before relay 70 75

34 will operate to open contact members 73. When overload relay 34 operates, the motor as well as the magnetizing coil 36 of the brake 3 is deenergized and, in consequence, the brake shoe 57 sets and the arm 11 will be moved to a position determined by the tension in the cable 72. Obviously if the controller plate 6 is moved to engage arm 11 in position *a*, a smaller angular movement of arm 11 is needed to deenergize the directional contactors and the accelerating contactors at the controller 4 than would be needed if the speed of operation of the motor had been higher, namely if the controller occupied any other position than position *a*. To thus make the operation of the overload relay have some definite relation with reference to the angular movement that would be needed for arm 11 when there is an excessive tension on cable 72, the actuating effect of coil 71 is made directly proportional to the angular movement of the lever or handle 7.

If the motor when operating be subjected to an excessive overload, the additive effect of coils 33 and 71 will open the contact members 73 of the overload relay 34, thereby deenergizing the directional contactor 18 and also deenergizing the accelerating contactors 41 and 46. The actuating or magnetizing coil 36 of the brake 3 is also deenergized by reason of the opening of the contact members 37, and the oscillating case 55 of the brake 3, since the brake shoes 57 immediately set, moves in a clockwise direction about the shaft of the armature to increase the tension in the lower balancing spring 59 and move the link 63 upwardly to thus rotate the gear 65, by the clockwise movement of the crank 64, in a clockwise direction thereby moving the shaft 66 connected to the arm 11 in a counter-clockwise direction by an amount sufficient to move the arm 11 to the neutral position, or position shown in the Figure. This proper angular movement must necessarily 40 follow by reason of the self-calibrating overload relay 34.

From the foregoing explanation it is apparent that an overload on the motor stops the winch and then the tension or weight on the cable is 45 measured. The movement of arm 11 is an indication of the weight being hoisted. When the weight thus measured is decreased to a certain value, the motor may restart to continue the hoisting of the load. On the other hand if the 50 weight increases above a certain value the motor restarts to pay out cable, as subsequently described.

Accelerating contactors 41 and 46, as well as the directional contactor 18, have an additional 55 gap in the circuits of their respective operating coils, namely, at the controller 4, by reason of the movement of arm 11 back to neutral position, for example, and since the overload relay also has its circuit for both coils 33 and 71 opened 60 by reason of the opening of the contact members 27 and 73, respectively, contact members 73 again close.

Closing of the contact members 73 will however, have no effect on the directional contactors 65 nor the accelerating contactors so long as there is an excessive tension in the cable 72, because as long as the tension persists, arm 11 will remain in the neutral or off position. After the tension has been relieved, which will normally occur automatically, and within a short interval of time, since the motor no longer operates the hoisting drum, the arm 11 moves back by reason of the actuation of the springs 58 and 59 to the 70 particular speed setting made by the at- 75

tendant when first accelerating the motor by moving the handle 7. When this occurs, the motor 2 is again automatically energized and the hoisting operation is resumed.

5 If for any reason, the tension in the cable 72 be very great, so that the movement of the arm 11 when the brake shoe 57 sets is out of proportion with respect to the overload that occurred on the overload relay 34, the arm moving 10 to position a' , for example, a reverse circuit is established for the motor 2 which circuit may be traced from the energized conductor 14 through arm 11, controller segment 12, brush 48, conductor 49, actuating coil 50 of the reverse 15 directional contactor 51 to the energized conductor 19. Closing of the directional contactor 51 establishes an energizing circuit for the magnetizing coil 36 of the brake 3 through the contact members 52 and also establishes a reverse 20 circuit for the motor armature 25 through the contact members 53 and 54. The cable 72 is thus paid out at a slow rate to relieve the tension therein.

25 If the arm 11 moves not only to position a' but all the way through to position c' , the accelerating contactors 41 and 46 are energized in exactly the manner hereinabove explained for the forward or hoisting operation of the motor and the paying out of the cable will thus occur at a comparatively rapid rate. For the reverse 30 operation just described, the oscillating casing 55 is, of course, released by the energization of the coil 36 and arm 11 would be immediately moved to the neutral position, thus preventing any substantial paying out of the cable 72. Normally, no great amount of cable needs to be paid out when there is a rise in tension in the cable 72, but to prevent the arm 11 from immediately opening the reverse circuit for the motor, 35 the directional contactor 51 is provided with a very low resistance short-circuited coil 80 to give it a considerable time constant. This time constant or delayed operation of the directional contactor 51 holds the contact members 52, 53 and 40 54 closed for an interval of time sufficient to pay out the necessary amount of cable 72 to relieve the tension.

45 If continuous reverse operation is desired, it is of course obvious that lever 7 may be moved 50 in the lowering or clockwise direction whereupon arm 11 will take positions a' , b' or c' as desired, and again the coil 71 will be automatically calibrated to have an operating effect proportional to the angular movement of the lever 7. 55 For the lowering direction, this is usually not so important, since an overload is not likely to occur, for in many instances the load may even be overhauling and the control is thus not symmetrical although it is shown substantially symmetrical and would be symmetrical except for the fact that directional contactor 51 is provided with a timing circuit.

60 With the devices heretofore supplied to the market, the motor had to be a motor having a continuous rating, that is, one that had to be comparatively large to successfully operate continuously with a full load on the winch 1 in actual operation. Since the demand on a hoist or winch motor is always intermittent, a rest 65 period being interposed between successive operations, it would constitute a valuable advance in the art to provide control means for a winch and the driving motor therefor which would permit the use of an intermittently rated motor.

An intermittently rated motor can be much smaller and the equipment thus much cheaper if such motor can be used. My control permits the use of such smaller motor and so controls the equipment that the smaller motor is nevertheless not overheated and the insulation will not be injured by reason of the rest periods allowing for proper cooling of the motor after each operation. With my system of control, this object is attained, as it is obvious that the motor 10 can be an intermittently rated motor and the cost of the equipment is thus very much reduced and its efficiency is improved. This is particularly important where the winch is to be installed on board ship where the question of weight 15 is always an important one.

I am fully aware that my invention is susceptible of other modifications and applications not herein specifically disclosed, particularly by those skilled in the art after having had the 20 benefit of the teachings of my invention. It is, therefore, to be understood that my invention is not to be limited to the specific circuit arrangements shown nor the application made but is only to be limited by the scope of the claims 25 hereto appended and the pertinent prior art.

I claim as my invention:

1. In a system of control for a winch, in combination, a winch having a drum and a hauling cable wound thereon, a motor for driving the 30 winch, an electromagnetic brake having a movable drum connected to the motor shaft and a brake shoe adapted to hold the motor shaft and thus the winch in position, said brake shoe being mounted on a spring-biased base adapted to oscillate about the center of the brake drum, a controller arm adapted to be moved by the spring-biased base when said brake shoe engages the 35 brake drum proportionally to the tension in the cable, an overload relay adapted to deenergize the 40 motor and set the brake shoe when a predetermined overload is on the motor, and means, operable only when the motor is deenergized, for energizing the motor for haul in rotation when the 45 arm is moved by a decrease in the tension in the cable.

2. In a system of control for a motor operating a hoist, in combination, a hoist and a cable, a motor driving the hoist, a source of energy for the motor, overload means, adapted to be energized inversely proportional to the voltage impressed on the motor armature and proportional to the motor load, for disconnecting the motor from the source of energy, and means, responsive, after the motor is deenergized, to the tension in 55 the cable, adapted to reenergize the motor.

3. In a system of control for a motor operating a hoist, in combination, a winch operating a cable, a motor driving the winch, a source of energy for the motor, a controller, a lever of the controller 60 adapted to be actuated in response to the tension in the cable after the motor is deenergized, controller means adapted to be moved relative to the lever to provide a certain speed setting for the motor, overload means, responsive to the load on the motor and the voltage impressed on the motor armature, adapted to disconnect the motor from the source of energy, and means adapted to move said lever to counteract the movement of said controller means as a function of the tension in 65 the cable after the motor is deenergized to thus prevent reenergization of the motor as long as the tension in the cable is above a certain value, and means reenergizing the motor by a movement 70 75

- of the lever when the tension decreases below a certain value.
4. In a control system for a winch, in combination, a motor for driving the winch, a controller adapted to select the voltage to be impressed on the motor, overload means, adapted to be energized additively by a current proportional to the motor current and by a current inversely proportional to the voltage selected to be impressed on the motor armature, to deenergize said motor.
5. In a control for a winch, in combination, a motor for driving the winch, a controller adapted to select the voltage to be impressed on the motor, overload means, adapted to be energized additively by a current proportional to the motor current and by a current inversely proportional to the voltage selected to be impressed on the motor armature, to deenergize said motor, and means responsive to the tension in the cable of the winch to reenergize the motor.
6. In a control for a winch, in combination, a motor for driving the winch, a brake, a controller for the motor comprising an arm adapted to be moved as a function of the tension in the winch cable after the motor is deenergized and the brake set and a member movable with reference to the movable arm to thus control the speed of the motor, overload means responsive jointly to overload and the position of the movable member to deenergize the motor and set the brake, and means adapted to reenergize said motor for hoist rotation, after a specified overload, when the cable tension has decreased to a predetermined value.

7. In a system of control, in combination, a motor, a source of energy, a controller comprising an arm adapted to be adjusted in position to a

predetermined normal load on the motor, a controller element adapted to be movable with respect to the arm to energize said motor, means for nullifying the effect of the movement of the controller element with reference to the arm and means responsive to the torque on the motor shaft to reenergize said motor, said means being responsive to the torque on the motor shaft only after the motor is deenergized.

8. In a system of control for a motor operating a winch, in combination, a winch having a drum and a hoist cable actuated by the drum, a motor operating the winch, a brake drum operable with the motor armature, a brake shoe, a resilient mounting for the shoe adapted to be rotatably shifted in position, when the brake shoe is set, by an amount determined by the torque on the motor shaft, after the motor has been deenergized, as determined by the tension in the cable, and means for energizing the motor either to haul in the cable, or pay it out, in response to the angular shift in the mounting by reasons of variations in the tension of the cable, said means being responsive to the cable tension only after the motor is deenergized.

9. In a system of control for a motor, in combination, a source of energy, a motor adapted to be energized from said source, overload means, responsive jointly to the motor current and inversely to the voltage impressed on said motor, adapted to disconnect said motor from said source of energy, and means responsive, after the actuation of said overload means, to reenergize said motor as a function of the torque on the motor shaft.

EDWARD M. CLAYTOR.
